Primary Examiner — T Chase Nelson*Assistant Examiner* — Kelly L Gross(57) **CLAIM**

The ornamental design for an electronic sphygmomanometer, as shown and described.

DESCRIPTION

FIG. 1 is a front view of the electronic sphygmomanometer showing our new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof;

FIG. 8 is a perspective view thereof; and,

FIG. 9 is an enlarged view of the encircled area 9 in FIG. 4. The broken lines in FIGS. 4 and 9 define the boundaries of the call out for the enlarged FIG. 9 and form no part of the claimed design.
